Louis C. Schermerhorn

BY
Marshall G. Dearborn

ATTORNEY'S

UNITED STATES PATENT OFFICE.

LOUIS C. SCHERMERHORN, OF PATERSON, NEW JERSEY.

STRING-ANCHORAGE FOR TUNING-PEGS.

1,295,215.

Specification of Letters Patent. Patented Feb. 25, 1919.

Application filed February 19, 1918. Serial No. 218,019.

To all whom it may concern:

Be it known that I, LOUIS C. SCHERMERHORN, a citizen of the United States of America, and a resident of Paterson, county 5 of Passaic, and State of New Jersey, have invented certain new and useful Improvements in String-Anchorages for Tuning-Pegs, of which the following is a specification; reference being had to the accompanying drawings, forming a part thereof.

My invention relates to improvements in string anchorage for tuning pegs and its object is to provide a simple and effective device for facilitating the connection of a 15 string of a musical instrument to the peg by means of which the tension of a string is varied and for securely attaching the string to its peg.

In order that my invention may be thoroughly understood I will now proceed to describe the same in the following specification and will then point out the novel features thereof in appended claims.

Referring to the drawings:

25 Figure 1 is a plan view of the head of a violin with its usual tuning pegs provided with anchorage devices made according to and embodying this invention.

30 Figs. 2, 3 and 4 are sectional end elevations through the neck of the violin at one of the tuning pegs with the neck, peg, anchorage member, and a string shown in different relative positions to illustrate the manner in which the arrangement is used.

35 Fig. 5 is a longitudinal section on a larger scale, of the same parts in the positions in which they are shown in Fig. 4, the section being taken on the line 5—5 of the latter figure.

40 Fig. 6 is a perspective view also on an enlarged scale of the anchorage collar.

Like characters designate corresponding parts in all the figures.

10 designates the outer portion of the neck 45 of a violin, 11 its scroll, and 12 13 the sides of its head in which the pegs are supported; and the transverse string holes therethrough, by 18. The strings are designated in the drawings by the reference numeral 19.

50 The tapered tuning pegs are designated 14, 15, 16 and 17. These parts are all of standard form and construction. In fact it is one of the advantageous features of this invention that no change to the instrument to 55 which it is applied, is necessary.

On each peg between the sides 12 of the

head in which the pegs fit, is placed a collar 20 of thin, flexible material, preferably having some resiliency, such as metal or fiber. This collar is tapered to fit the peg but does 60 not completely surround the peg as it is split longitudinally and spread somewhat to leave an open space 21. It is also made shorter than the distance between the sides 12 and 13 of the neck.

65 I will now describe the manner in which this device is used showing, for example, the way an A string is fastened to its peg 14. The peg is withdrawn slightly from the sides 12—12 to the position in which it is 70 shown in Fig. 2, with the collar 20 against the side 12 and away from the side 13 a sufficient distance to enable one to thread the string 19 through the hole 18 until it protrudes through the peg as at 22 in Fig. 2, 75 and with the open side 21 of the collar in alignment with the entrance to the hole. The peg 15 is then pushed into its seats in the sides 12 and 13 as shown in Fig. 3. As the smaller end of the locking collar abuts 80 against the inner surface of the side 12, it will not move during this movement of the peg, and this will result in the part of the string which protrudes through the peg, being bent over as at 23 in Figs. 3, 4 and 5 85 under the collar 20, the part of which opposite the opening 21, will be forced away from the peg a sufficient distance to receive this part of the string. Now the peg is rotated to wind the string around the outside 90 of the locking collar as shown at 24 in Figs. 4 and 5, thereby binding the collar onto the end 23 of the string. This operation is easily and quickly accomplished and results 95 in a secure attachment of the string to the peg.

100 I have described the operation of securing the A string to its peg as, with a violin without this device, it is more difficult to secure this string to its peg than the others because the space around this peg is more limited and the part of the peg between the sides 12 and 13 less accessible. It is obvious that the other strings are secured to their pegs in a similar manner.

105 While I have described this invention as applied to a violin, it is not, of course, limited to this instrument and I intend no limitations other than those imposed by the appended claims.

110 What I claim is:

1. A string anchorage comprising a split tapered collar, adapted to be placed about

- a rotatable tapered peg having a transverse opening for the reception of a string, and movable longitudinally on said peg to uncover both ends of said opening and to a position overlapping one end of said transverse opening.
2. A string anchorage comprising a tapered collar adapted to be placed about a rotatable tapered peg having a transverse opening for the reception of a string, said collar being movable longitudinally on the peg to hold between its inner surface and an adjacent surface of the peg, an end of the string, and rotatable with the peg to cause the string to be wound about its outer surface to thereby clamp the string.
3. A string anchorage comprising a tapered collar adapted to be placed about a rotatable tapered peg having a transverse opening for the reception of a string, and movable longitudinally on the peg over said opening to receive between its inner surface and the surface of the peg a portion of a string inserted through said opening.
4. A string anchorage comprising a tapered collar adapted to be placed about a rotatable peg having a transverse opening for the reception of a string, and movable longitudinally on the peg over said opening to receive between its inner surface and the surface of the peg a portion of a string protruding through one end of said opening, said collar being constructed with transverse opening opposite the part thereof which receives such protruding part of the string, to form a clearance for the part of the string which protrudes from the opposite end of the transverse opening of the peg.
5. In combination with a tapered peg, a pair of spaced supporting members therefor, said peg having a transverse opening be-
- tween said members for the reception of a string, a collar shorter than the space between the supporting members placed about the peg between said members and movable longitudinally on the peg over said opening.
6. In combination with a tapered peg, a pair of spaced supporting members therefor, said peg having a transverse opening between said members for the reception of a string, a tapered collar shorter than the space between the supporting members, placed about the peg between said members, and movable longitudinally on the peg over said opening.
7. In combination with a tapered peg, a pair of spaced supporting members therefor, said peg having a transverse opening between said members for the reception of a string, a tapered collar split longitudinally, said collar being shorter than the space between the supporting members and being placed about the peg between said members, and movable longitudinally on the peg over said opening to receive between its inner surface and an adjacent surface of the peg a portion of a string and arranged to have another part of the string wound around its outer surface.
8. In combination with a string, a rotatable peg having a transverse opening for the string, an anchorage member on the peg having a portion of the string which protrudes from one end of the opening between itself and the peg, and a part of the string which protrudes from the other end of the opening wound over the outer surface of the member.

In witness whereof, I have hereunto set my hand this 31 day of January, 1918.

LOUIS C. SCHERMERHORN.
